SHARPENER FOR CUTTING BLADES

Richard E. Fox, Northbrook, Ill., assignor to Fox Howard Corporation, a corporation of Illinois

Application June 16, 1958, Serial No. 742,376

5 Claims. (Cl. 51—241)

This invention relates to a sharpener for the cutting blades of power lawn mowers, and is particularly concerned with a grinding unit and means for detachably securing the grinding unit to the drive shaft of the gasoline engine of a power lawn mower whereby it may be rotated by operation of the engine.

In accordance with the present invention, when the cutting blades of a power lawn mower become dull they may be removed and sharpened by means of a grinding unit detachably mounted on the starter housing without substantial loss of time. The grinding unit may be kept permanently in its mounted position on the starter housing, if desired, but is preferably removed from the starter housing when not being used, in order to protect it from accidental damage during the normal use of the mower.

Gasoline engines for power lawn mowers are usually provided with a vertical drive shaft having cutting blades mounted on its lower end. The present invention is particularly concerned with means for securing a grinding unit to a power lawn mower having a recoil starter. In mowers of this type the recoil starter is mounted in a housing secured to the top of the engine housing and is engaged with the upper end of the drive shaft which projects through the top of the engine housing. The top of the starter housing is apertured, and the grinding unit includes a base provided with a depending stem which projects through the aperture of the starter housing into threaded engagement with an axial bore provided in the drive shaft of the engine. The base of the grinding unit has a plurality of circumferential cams on its vertical wall.

The grinding stone is in the form of a flat disc mounted in a frame adapted to seat on the base of the grinding unit. The upper face of the grinding stone lies in a plane above the upper edge of the frame, and the frame has a depending circular flange provided with inwardly extending bosses engageable with the cams of the base to hold the grinding stone in fixed relationship to the base.

The structure by means of which the above mentioned and other advantages of the invention are attained will be described in the following specification, taken in conjunction with the accompanying drawings, showing a preferred illustrative embodiment of the invention, in which:

Figure 1 is a perspective view of a grinding unit mounted on top of a recoil starter for a gasoline engine in accordance with the invention;

Fig. 2 is a cross sectional view, taken along the line 2—2 of Fig. 1 with parts of the starter mechanism omitted for clarity;

Fig. 3 is a top plan view of the base of the grinding unit;

Fig. 4 is a perspective view of the base of the grinding unit;

Fig. 5 is a bottom perspective view of the grinding stone and frame in which it is mounted; and

Fig. 6 is a bottom plan view of the frame for holding the grinding stone.

Referring to the drawings, the reference numeral 2 indi-

2

cates a gasoline engine for a power lawn mower. Engine 2 is mounted in a housing having a top wall 3 through which the upper end of the drive shaft 4 projects. An axial bore 5 is drilled into the upper end of drive shaft 4. A recoil starter 6 is mounted in a housing 7 having legs 8 secured to top wall 3 in any suitable manner. The top wall 9 of housing 7 has an aperture 10 aligned with axial bore 5. The gasoline engine and the recoil starter are conventional except for axial bore 5 and aperture 10, and therefore will not be specifically described. The purpose of axial bore 5 and aperture 10 will be hereinafter described.

The grinding unit, indicated generally by the reference numeral 11, comprises a grinding stone 12 mounted in a frame 13 which in turn is supported by a base 14. The grinding stone may be of any suitable shape, but preferably is in the form of a flat cylindrical disc. Frame 13 comprises a wall 15 having a horizontal cross sectional area conforming to the horizontal cross section of the lower surface of grinding stone 12, and a vertical wall 16 conforming to the periphery of the grinding stone. Wall 15 is disposed intermediate the height of wall 16 to provide an upstanding flange 17 and a depending skirt 18. Flange 17 prevents lateral displacement of grinding stone 12 which is firmly held by wall 15 and flange 17 in any suitable manner, as, for example, by adhesive.

Grinding stone 12 is thicker than the height of flange 17 and its grinding surface extends above the upper edge of the flange. Although the grinding surface is preferably flat, it may have any desired configuration. The lower edge portion of depending skirt 18 is provided with circumferentially spaced inwardly extending bosses 19 for a purpose hereinafter described. The number of bosses 19 may be varied, but they are spaced uniformly of the circumference of the skirt regardless of the number provided. Each boss extends circumferentially of skirt 18 and the upper edges of the bosses are spaced uniformly from the underside of wall 15.

Base 14 comprises a cup-shaped member 20 having a cylindrical wall 21 adapted to fit within skirt 18 and a threaded stem 22. Stem 22 is preferably in the form of a bolt adapted to engage the interior of axial bore 5. Bore 5 and stem 22 are threaded to interfit. Stem 22 extends through an aperture 23 in the bottom 24 of the cup-shaped member 20 and is secured thereto by a flat washer 25 and a lock washer 26. Nuts 27 and 28 are threaded on stem 22 to hold washers 25 and 26 in place. A lock washer 29 is positioned on stem 22 between the top of drive shaft 4 and the underside of nut 28. The washers 25, 26, 29 and nuts 27, 28 cooperate with stem 22 to secure base 14 rigidly to drive shaft 4 and to thereby insure rotation of base 14 with the drive shaft.

The upper edge portion of wall 21 is provided with a series of cams 30 extending in a general horizontal direction and embossed outwardly to provide cam risers extending outwardly at right angles to wall 21. Cams 30 are symmetrical and are spaced uniformly around the circumference of base member 14. The number of cams is the same as the number of bosses 19 provided on skirt 18 and the spaces between the ends of adjacent cams is greater than the length of each boss 19. Frame 13 can be positioned on base 14 by dropping it vertically on the base, with bosses 19 passing vertically between cams 30 to seat the wall 15 on the upper edge of wall 21.

The lowermost surface of each cam 30 is spaced from the upper edge of wall 21 a distance greater than the space between the upper edge of each boss 19 and the underside of wall 15. Accordingly, rotation of drive shaft 4 and base 14 will cause each cam 30 to interlock with one boss 19 when frame 13 is seated on base 14. The interlocking engagement of frame 13 with base 14 will

cause grinding stone 12 to rotate with drive shaft 4 to sharpen any blades held against its exposed grinding surface.

Although I have described a preferred embodiment of the invention in considerable detail, it will be understood that the description thereof is intended to be illustrative, rather than restrictive, as many details may be modified or changed without departing from the spirit or scope of the invention. Accordingly, I do not desire to be restricted to the exact construction described.

I claim:

1. In combination with a lawn mower engine having a vertical drive shaft and a threaded axial bore extending downwardly into the top of said drive shaft, a grinding unit comprising a base provided with a depending stem threaded to engage said axial bore, a frame mounted on said base, and a grinding stone rigidly secured in said frame.

2. In combination with a lawn mower engine having a vertical drive shaft and a threaded axial bore extending downwardly into the top of said drive shaft, a grinding unit comprising a cup-shaped base provided with a plurality of outwardly extending cams and a depending stem threaded to engage said axial bore, a frame having a horizontal wall and a vertical wall cooperating to support a grinding stone, said vertical wall having inwardly extending bosses engageable with said cams to detachably secure said frame to said base.

3. In combination with a lawn mower engine having a vertical drive shaft and a threaded axial bore extending downwardly into the top of said drive shaft, a grinding unit comprising a cup-shaped base having a bottom and a cylindrical vertical wall, a stem depending from said bottom and threaded to engage said axial bore, a plurality of outwardly extending cams uniformly spaced circumferentially of said cylindrical wall, a frame having a circular skirt encircling said cylindrical wall, a plurality of bosses extending inwardly from said skirt, each of said bosses

being of less length than the space between adjacent cams, said bosses being spaced uniformly circumferentially of said skirt, whereby said bosses may be passed through the spaces between said cams and engaged with said cams to detachably secure said frame to said base, and a grinding stone rigidly secured in said frame.

4. In combination with a power lawn mower engine provided with a vertical drive shaft, a grinding unit comprising a base, a frame, and a grinding stone rigidly secured in said frame, said drive shaft having a threaded axial bore extending downwardly into its upper end, said base having a depending stem and a series of cams, said stem being threaded to fit in said axial bore, said frame being seated on the upper edge of said base and having a series of bosses adapted for interlocking engagement with said cams.

5. In combination with a power lawn mower engine provided with a vertical drive shaft, a recoil starter engaging said drive shaft, a housing enclosing said starter, 20 said housing having a top wall having a centrally disposed aperture in alignment with the upper end of said drive shaft, a grinding unit comprising a base, a frame, and a grinding stone rigidly secured in said frame, said drive shaft having a threaded axial bore extending downwardly 25 into its upper end, said base having a depending stem and a series of circumferentially spaced cams, said stem being adapted to pass through said aperture and threaded to fit in said axial bore, said frame being seated on the upper edge of said base and having a series of bosses adapted for 30 interlocking engagement with said cams.
